YARN GUIDE FOR BRAIDING CARRIERS

Max Krissiep, Wyomissing, Pa., assignor to Textile Machine Works, Wyomissing, Pa., a corporation of Pennsylvania

Application March 30, 1935, Serial No. 13,799

7 Claims. (Cl. 96—13)

This invention relates to thread or yarn carriers for braiding machines and the like, and more particularly to special guide means therefore, for facilitating the passage of fibrous, metallic, or other threads, strands or wires from the yarn supply on the carrier to the braiding point of the machine.

Heretofore, in braiding carriers, and more particularly in cases where each carrier supports and controls a single wire strand or a plurality of wire strands in braiding a fabric, a rotatable guide roller has been used to reduce friction and resultant wear between the wire and the carrier in the passing of the wire over the guiding members of the braiding carrier as the wire or group of wires passes from the supply spool or bobbin on the carrier to the braiding point of the machine. The mounting for the guide roller is normally supported in a fixed portion of the carrier frame for pivotal movement about a vertical axis substantially tangent to the base of the groove in the guide roller so that the groove of said guide roller is at all times maintained in a plane disposed substantially in line with the braiding point of the machine as the carriers traverse their respective intersecting serpentine paths on the carrier raceplate of the machine. Heretofore this has been accomplished by means of a guide eye, through which the wire or wires passed in extending from the groove of the guide roller to the braiding point of the machine.

When a multiplicity of wire strands were passed simultaneously as a single unit from each braiding carrier to the braiding point of the machine, one or more of the strands at times would rise out of the groove of the guide roller, during the braiding operation, due to non-uniform tensioning of the several strands during the winding thereof on the supply bobbin, which permitted the vagrant strands to flex laterally beyond the peripheral edge of the guide roller, usually resulting in the dropping of such wire strand or strands to one side or the other of the guide roller when the slack in the vagrant strand diminished, thereby causing the formation of imperfect fabric if such roller hopping of the strand was not at once detected by the operator of the machine.

One object of my invention is to provide the carrier, adjacent the guide roller, with thread-confining means for preventing a thread or wire strand from moving laterally beyond the planes of the side edges of the roller groove.

A further object is to provide the guide roller

with guard walls for preventing a thread or wire from hopping over the peripheral edge of the roller and becoming jammed between the sides of the roller and the bearings between which said guide roller is rotatably mounted by extending the guard walls vertically from said bearings along the opposite sides of the guide roller with portions of the inner surfaces of the guard walls projecting laterally in opposite directions over the side edges of the roller and in close proximity to the outer peripheral edges of the guide roller.

A further object is to provide a swivel mounting for the braiding carrier thread guide roller wherein the mounting is provided with thread-confining walls between which the guide roller is rotatably mounted and the thread travels and wherein said walls function to keep the groove of said guide roller in a plane in line with the braiding point of the machine at all times.

With these and other objects in view, which will be apparent from the following detailed description of the illustrative embodiment of the invention shown in the accompanying drawing, my invention resides in the novel mechanism and means for operating the same, as hereinafter more particularly pointed out in the claims.

In the drawing:

Figure 1 is a side elevational view of a braiding carrier illustrating the principles of the present invention as applied thereto;

Fig. 2 is an enlarged front elevational view of the guide shown in Fig. 1;

Fig. 3 is a transverse sectional elevational view taken on the line 3—3, Fig. 1;

Fig. 4 is a vertical sectional view taken on the line 4—4, Fig. 2; and

Fig. 5 is a plan view illustrating the relation between the thread or wire and the guide roller.

In braiding carriers, where a multiplicity of wire or other relatively stiff threads or strands is intended to be drawn simultaneously and to pass from a common supply spool or bobbin on the carrier to the braiding point of the machine concurrently, as a single unit, the tension applied to the respective strands of which the unit is composed, during the winding of the several strands at one time upon the common supply bobbin or spool, is sometimes irregular, consequently one or more of said individual wire strands will be wound more loosely in said supply package than the others and as the plurality of wire strands is drawn as a unit from the supply bobbin by the interbraiding of a

number of such units at the braiding point of the machine during the braiding operation, any such looseness in any one of the separate wire strands will cause the loose strand to bulge relative to the line of movement of the unit, whereby the loose strand will frequently move out of the groove of the guide roller. In order to assure the return of the vagrant strand to said groove, it is the purpose of the present invention 10 to provide guard walls beyond the periphery of the roller and in planes which may advantageously coincide with the planes of the oppositely disposed side edges respectively of the roller groove and which may extend vertically 15 from the bearings between which said guide roller is rotatably mounted, with a portion of said guard walls projecting transversely over the outside edges of the face of said guide roller.

A conventional braiding carrier usually comprises a foot or base portion 10 having an upright standard or frame member 11 extending vertically therefrom, and on which the common thread or wire supply spool or bobbin 12 is mounted. In an upper transverse portion 13 of the frame member 11 in the present instance is a vertical rotatably mounted tubular stud or eye 14 through which the wire or other strand, thread, etc. passes in its travel from the supply bobbin 12 to the braiding point of the machine. The swivel stud or eye 14 is mounted for free rotation about its vertical axis by means of ball bearings 15 and 16 which are seated in a housing 17 formed in the upper transversely extending portion 13 of said frame member, between an annular shoulder 14a formed on and at the upper end of the swivel eye 14 and a collar 14b mounted on the lower end thereof.

Extending vertically from the top of the eye 14 is a pair of laterally spaced arms 18 and 19, which are provided with bearings 20 and 21 respectively, formed in the upper outwardly turning end portions of said arms.

Journaled in the bearings 20 and 21 is a pin or axle 22 on which is rotatably mounted a guide roller 23. The guide roller 23 is made freely rotatable on the pin 22 by means of a ball or other anti-friction bearing 24.

Extending substantially vertically from the bearings 20 and 21 of the arms 18 and 19 respectively, and adjacent the oppositely disposed side edges respectively of the guide roller 23, is a pair of plates or lugs 25 and 26 affording, in the present instance, substantially parallel oppositely disposed segmental guard walls 27 and 28 which extend circumferentially and radially with respect to and above the outer peripheral edges respectively of said guide roller 23.

That portion of the inner surface of each of the plates or lugs 25 and 26 which constitute the guard walls 27 and 28 project toward each other transversely of and in close proximity to the outer peripheral edge 29 of the guide roller 23 and are respectively disposed in planes substantially coincident with the planes of the side edges 30 and 31 of the groove 32 in the roller 23, so that any vagrant strand or thread which may leave the groove 32 of said guide roller 23 will be prevented from dropping or entering between the outer side edges of said guide roller and the inner sides of the arms 25 and 26, and will be directed back into the groove 32 as and when the bulge in the wire diminishes as the slack in the wire is taken up.

From the illustration in Fig. 5, it will be clearly seen that due to the tangential relation be-

tween the axis of the stud 14 and the base of the groove 32 of the roller 23 the guide roller 23 and the guide eye swivel stud 14 may be turned in any direction by means of the wire contacting either one of the inner surfaces 27 or 28 of the guards 25 and 26 respectively, and that said wire being taut between the braiding carrier and the braiding point of the machine, the plane of the groove 32 of the guide roller 23 will always be held in a straight line pointing to said braiding point as the braiding carriers traverse their intertwining and intersecting courses over the raceplate of the braiding machine beneath the braiding point thereof.

While I have shown and described a preferred embodiment of my invention, obviously various changes in the construction may be made without departing from the scope of my claims; for example, the guard surfaces 27 and 28 may be of any desired contour and may be in convergent or divergent relation to each other rather than maintaining the parallel relationship shown, and the plates 25 and 26 on which said guard surfaces are formed may be separate from and secured to the swivelled mounting for the guide 25 roller 23 if desired.

I claim:

1. A braiding carrier comprising a rotary thread guide, a mounting for said guide comprising a pair of laterally spaced brackets affording a rotary support for said guide therebetween, a pivot stud supporting said brackets and arranged with its axis perpendicular to the axis of rotation of said guide, a bearing in said carrier for rotatably supporting said pivot stud, and a pair of guiding walls extending from said brackets respectively beyond the peripheral edge of the guide adjacent opposite sides of the guide where the thread leaves the guide in passing from the carrier, for preventing lateral displacement of the thread relative to the guide and for swinging said guide about said stud axis to align the guide at all times with the line of movement of the thread in leaving the carrier.

2. A braiding carrier comprising a rotary thread guide, guide means for maintaining the thread in registered position on said guide, and fixed separate guide walls on opposite sides of the thread guide positioned to engage thread leaving the guide and deviating in either direction from alignment with the guide means for retaining the thread in a zone spaced from the rotary guide in substantial alignment with the thread on said guide.

3. A braiding carrier comprising a rotary thread guide, a pair of laterally spaced brackets affording rotary support for said guide therebetween, a pivot stud supporting said brackets and arranged with its axis perpendicular to the axis of rotation of said guide, a bearing in said carrier for rotatably supporting said pivot stud, and a pair of guide walls extending from said brackets respectively and beyond the peripheral edge of the guide adjacent opposite sides thereof arranged to engage the thread in a position offset from the axis of rotation of said pivot stud upon deviation of the thread in either direction from alignment with the thread guide to bring said guide into alignment with the thread by rotation of the pivot stud.

4. A braiding carrier comprising a circumferentially grooved rotary thread guide and relatively fixed guiding walls at opposite sides respectively of said guide, extending toward each other

and overhanging the periphery of said guide where the thread leaves the guide in passing from the carrier for preventing lateral displacement of the thread relative to the guide and preventing the thread from getting between the fixed guide walls and the rotary guide.

5. A braiding carrier comprising a circumferentially grooved rotary thread guide and relatively fixed guiding walls at opposite sides respectively of said guide, extending toward each other and overhanging the periphery of said guide at the opposite sides of the groove in said guide and circumferentially of and adjacent the peripheral edge of said guide where the thread leaves the guide in passing from the carrier for preventing lateral displacement of the thread relative to the guide and preventing the thread from getting between the fixed guide walls and the rotary guide.

10 6. A braiding carrier comprising a rotary thread guide, means for guiding the thread in registered position on said guide, a pair of laterally spaced brackets affording rotary support for said guide therebetween, a pair of guiding walls 15 extending from said brackets respectively, and

lateral extensions on said walls projecting toward each other and overhanging the peripheral edge of the guide adjacent opposite sides of the guide where the thread leaves the guide in passing from the carrier for preventing lateral displacement of the thread relative to the guide and preventing the thread from getting between the fixed guide walls and the rotary guide.

15 7. A braiding carrier comprising a circumferentially grooved rotary thread guide, a pair of laterally spaced brackets affording rotary support for said guide therebetween, a pair of guiding walls extending from said brackets respectively, and lateral extensions on said walls projecting toward each other, overhanging the peripheral edge of the guide adjacent opposite sides of the guide where the thread leaves the guide in passing from the carrier and extending to the planes of the side edges respectively of the guide groove 20 for preventing lateral displacement of the thread relative to the guide and preventing the thread from getting between the fixed guide walls and the rotary guide.
